2,615,494

COLLAPSIBLE CHAIR-STICK

Anthony F. Ciaramella, New York, N. Y.

Application August 5, 1949, Serial No. 108,809

3 Claims. (Cl. 155—41)

1

This invention relates to chairs, and more specifically to a collapsible chair which is easily converted into a walking stick.

One of the primary objects of this invention is to provide a chair having foldable supporting legs and seat supporting arms whereby the chair may be collapsed to occupy a minimum amount of space.

A further object of this invention is to provide a chair having a flexible seat element, foldable supporting legs and seat supporting arms, the seat element being foldable about the arms and legs when these elements are folded into their collapsed position.

Another object of this invention is to provide, in a device of the type described, means for limiting the movement in one direction of the supporting legs and seat supporting arms.

A still further object of this invention is to provide means whereby movement of any one leg or seat supporting arm transmits equal increments of movement to the associated legs and arms.

As a further object of this invention it is proposed to provide means for maintaining a flexible seat in distended position about the folded legs and seat supporting arms.

Still another object of this invention is to provide a collapsible chair which is inexpensive to manufacture, simple to operate, and of durable quality.

Other and further objects and advantages of this invention will become apparent from the following specification when read in conjunction with the accompanying drawings, in which:

Figure 1 is a side elevation of the collapsible chair-stick constructed in accordance with this invention, the elements thereof being shown in their unfolded, or seat forming positions;

Figure 2 is a side elevation showing the elements in their folded or collapsed positions, whereby the device may be employed as a walking-stick or cane;

Figure 3 is a top plan view of the chair shown in Figure 1;

Figure 4 is a cross-sectional view, partially in elevation, taken on the line 4—4 of Figure 1;

Figure 5 is a cross-sectional view taken on the line 5—5 of Figure 4;

Figure 6 is a cross-sectional view, partially in elevation, taken on the line 6—6 of Figure 1;

Figure 7 is a cross-sectional view taken on the line 7—7 of Figure 6, illustrating details of the bracing structure;

Figure 8 is a cross-sectional view taken on line 8—8 of Figure 6; and

2

Figure 9 is a partial side elevation showing relative movement of the seat supporting arms and bracing structure as the seat is collapsed.

Referring now more particularly to the drawings, reference numeral 2, indicates, in general, a foldable or collapsible chair constructed in accordance with this invention. Chair 2 comprises (Figure 1) a flexible seat 4 of rectangular configuration having arcuate, notched corners 6. As seen in the drawings, the marginal edge of each side 8 is folded and stitched at 10 to form a longitudinally extending open ended tube 12. A chain or cable 14 is disposed in each tube 12, the ends of chain 14 being connected to securing rings 16 or 16'.

Four diverging seat supporting arms 18, 20, 22, and 24 rise from a rectangular support block 26 at intervals of 90°. A transverse bore 28, see Figures 1 and 3, is provided adjacent the upper end 20 of arm 18, and ring 16' is permanently mounted therethrough. Arms 20, 22 and 24 are each notched at the outer sides of their upper ends, as indicated at 30, 32 and 34, respectively, to detachably secure rings 16 thereto.

Supporting legs 36, 38, 40 and 42 diverge downwardly and outwardly from support block 26, the upper end of leg 36 being pivotally connected to a pin 44 on which the lower end of arm 18 is also pivotally mounted on the block 26. Similarly, arms 20, 22 and 24, and legs 38, 40 and 42, are mounted, respectively on pins 46, 48 and 50 which extend also through the support block.

As seen in Figures 4 and 5, laterally inwardly projecting, triangular abutments 52 limit the degree of outward movement of the adjacent arms and legs.

Bracing structures are provided intermediate the ends of the arms and legs, respectively, and comprises a cross shaped, connecting element 54 having arms 56 pivotally connected by pins 58 with one end of strut 60, the other end thereof being pivotally connected at 62 with an arm 18, 20, 22 and 24, or a leg 36, 38, 40 and 42.

From Figures 1 and 6 it will be noted that when the chair has been unfolded, bracing struts 60 for the supporting arms lie in a common horizontal plane parallel to, but spaced from bracing struts 60 for the supporting legs, the last named struts also residing in a common plane. From Figures 1, 2, 4 and 5 it is also seen that arms 18 and 36 are in the same vertical plane containing the oppositely disposed arm 22 and leg 40. Similarly, supporting arm 24 and supporting leg 42 are in the same vertical plane as the oppositely disposed support arm 20 and leg 38 being at right angles to each other.

The construction of the foldable chair 2 is completed by providing rows of snap fastening elements 64, 64' along two opposed edges of the flexible seat 4, and an inverted hook 66 on leg 36, to serve a purpose to be described.

The foregoing description relates to the component elements of the chair and relative positions as illustrated in Figures 1, 3, 4 and 5, the chair being unfolded. If it be desired to collapse or fold the chair, to the position shown in Figure 2, rings 16 are detached from slots 32, and opposed arms 18, 22 and 20, 24 (Figure 9) are then pivoted toward each other on their respective pivot pins, elevating connecting element 54 and the adjacent ends of struts 60.

Thereafter opposed legs 36, 40 and 38, 42 are similarly folded toward each other, the associated connecting element 54 and adjacent ends of struts 60 being forced downwardly.

After these two operations have been completed, flexible seat 4 is wrapped about arms 18, 20, 22 and 24, and about the upper ends of legs 36, 38, 40 and 42. Snap fastening elements 64 and 64' are then engaged to maintain the arms and legs in their folded positions, and ring 16" is forced over hook 66 to hold the seat in distended position. In this collapsed form, the device may be utilized as a walking stick or cane.

To convert to a chair, the above operations are carried through, but in reverse order.

Having set forth the details of one embodiment of my invention, it will be understood that the same has been offered by way of illustration and example, and that the invention is only to be limited by the scope of the following claims.

I claim:

1. In a collapsible chair, a support block formed with a central opening, a plurality of upper arms having lower ends positioned in the opening of the block, a plurality of lower arms having upper ends positioned in the block opening, with the lower and upper ends of adjacent upper and lower arms pivoted together and to the block whereby the upper and lower arms can swing from parallel relation to divergent relation, the said block opening defining side surfaces having divergent upper and lower portions serving as abutments for the related arms limiting divergent movement of the arms, and foldable struts extending between laterally adjacent upper and lower arms and pivoted thereto for holding the arms in divergent relation and in engagement with the abutments.

2. In a collapsible chair, a support block formed with a central opening, a plurality of upper arms having lower ends positioned in the

opening of the block, a plurality of lower arms having upper ends positioned in the block opening, with the lower and upper ends of adjacent upper and lower arms pivoted together and to the block whereby the upper and lower arms can swing from parallel relation to divergent relation, the said block opening defining side surfaces having divergent upper and lower portions serving as abutments for the related arms limiting divergent movement of the arms, and foldable struts extending between laterally adjacent upper and lower arms and pivoted thereto for holding the arms in divergent relation and in engagement with the abutments, and pivot means pivoting the arms in the block opening comprising pivot pins engaged in the block and extending across the block opening.

3. In a collapsible chair, a support block formed with a central opening, a plurality of upper arms having lower ends positioned in the opening of the block, a plurality of lower arms having upper ends positioned in the block opening, with the lower and upper ends of adjacent upper and lower arms pivoted together and to the block whereby the upper and lower arms can swing from parallel relation to divergent relation, the said block opening defining side surfaces having divergent upper and lower portions serving as abutments for the related arms limiting divergent movement of the arms, and foldable struts extending between laterally adjacent upper and lower arms and pivoted thereto for holding the arms in divergent relation and in engagement with the abutments, and pivot means pivoting the arms in the block opening comprising pivot pins engaged in the block and extending across the block opening, a single pivot being provided for pivoting the lower end of and the upper end of laterally adjacent upper and lower arms.

ANTHONY F. CIARAMELLA.
